UNITED STATES PATENT OFFICE.

OLIVER W. SABOLD, OF BOYERTOWN, PENNSYLVANIA, ASSIGNOR TO THE COLEBROOKDALE IRON COMPANY, OF POTTSTOWN, PENNSYLVANIA.

DESIGN FOR A CROSS-BAR FOR SAD-IRONS.

SPECIFICATION forming part of Design No. 30,961, dated June 6, 1899.

Application filed January 19, 1899. Serial No. 702,726. Term of patent 14 years.

To all whom it may concern:

Be it known that I, OLIVER W. SABOLD, a citizen of the United States, residing at Boyertown, in the county of Berks and State of Pennsylvania, have invented a new and useful Design for a Cross-Bar for Sad-Irons, of which the following is a specification.

This invention relates to a certain new design for cross-bars for sad-irons, and relates particularly to the formation or configuration of the top face thereof.

Referring to the accompanying drawings, Figure 1 is a perspective view of a cross-bar formed in accordance with my design. Fig. 2 is a top plan; and Fig. 3, a cross-section on line 3 3, Fig. 2, looking in the direction indicated by the arrow.

My design consists in the top face of the cross-bar, provided along its opposite side

edges with prominent raised parallel ribs or flanges *a a*, in cross-section semicircular at the top and extending between and merging into the side edges of the end bosses of the bar, so that the top face of the bar is formed with ornamental raised portions between the bosses of the bar in contradistinction to a plain top.

What I claim is—

The design for a cross-bar for sad-irons as shown and described.

In testimony whereof I have hereunto set my hand in the presence of two subscribing witnesses.

OLIVER W. SABOLD.
